(57) CLAIM

The ornamental design for a universal smart stylus pen, as shown and described.

DESCRIPTION

FIG. 1 is a perspective view of a first design for a universal smart stylus pen with an example removable, mating electronic device separated therefrom;

FIG. 2 is a right side view of the first design for the universal smart stylus pen of FIG. 1;

FIG. 3 is a front view of the first design for the universal smart stylus pen of FIGS. 1-2;

FIG. 4 is a left side view of the first design for the universal smart stylus pen of FIGS. 1-3;

FIG. 5 is a rear view of the first design for the universal smart stylus pen of FIGS. 1-4;

FIG. 6 is a top view of the first design for the universal smart stylus pen of FIGS. 1-5;

FIG. 7 is a bottom view of the first design for the universal smart stylus pen of FIGS. 1-6;

FIG. 8 is a perspective view of a second design for a universal smart stylus pen with an example removable, mating electronic device separated therefrom;

FIG. 9 is a front view of the second design for the universal smart stylus pen of FIG. 8 including an enlarged view of a portion of the second design; and,

FIG. 10 is a top view of the second design for the universal smart stylus pen of FIGS. 8-9.

The features shown in broken lines depict environmental structure only and form no part of the claimed design.

FIGS. 1-5 and 8-9 present break lines, in the form of parallel wavy lines or S-breaks, along a length of the first design for the universal smart stylus pen and the second design for the universal smart stylus pen to represent that a length of these designs may be variable. The appearance of any portion of the first design for the universal smart stylus pen and the second design for the universal smart stylus pen between the break lines forms no part of the claimed design.
